(57) **CLAIM**

The ornamental design for a cosmetic container, as shown and described.

DESCRIPTION

FIG. 1 is a top perspective view of the closed container;
FIG. 2 is a bottom perspective view of the closed container;
FIG. 3 is a front view of the closed container;
FIG. 4 is a rear view of the closed container;
FIG. 5 is a right side view of the closed container;
FIG. 6 is a left side view of the closed container;
FIG. 7 is a top view of the closed container;
FIG. 8 is a cross section view of the closed container along line 8-8 of FIG. 7;
FIG. 9 is a cross section view of the closed container along line 9-9 of FIG. 7;
FIG. 10 is a bottom view of the closed container;
FIG. 11 is a top perspective view of the open container;
FIG. 12 is an upper cross section view of the open container along line 12-12 of FIG. 11;
FIG. 13 is a lower cross section view of the open container along line 13-13 of FIG. 11;
FIG. 14 is a bottom perspective view of the open container;
FIG. 15 is a front view of the open container;
FIG. 16 is a rear view of the open container;
FIG. 17 is a right side view of the open container;
FIG. 18 is a left side view of the open container;
FIG. 19 is a top view of the open container; and,
FIG. 20 is a bottom view of the open container.
